UNITED STATES PATENT OFFICE.

FRANCIS A. NOLAN, OF ST. PAUL, MINNESOTA.

SHOE-HEEL.

1,096,008.

Specification of Letters Patent. Patented May 5, 1914.

Application filed April 12, 1913. Serial No. 760,581. REISSUED

To all whom it may concern:

Be it known that I, FRANCIS A. NOLAN, a citizen of the United States, residing at St. Paul, in the county of Ramsey and State of Minnesota, have invented a new and useful Improvement in Shoe-Heels, of which the following is a specification.

An object of this invention is to provide an improvement in fasteners for detachable heels, whereby the fastener can be readily positioned on a shoe to receive a heel made of rubber or other resilient material and hold it firmly in position so that it cannot become unintentionally detached and at the said time permitting the ready removal of the heel when desired for purposes of interchanging and prolonging the life of heels or renewing them.

More particularly this invention is an improvement upon the construction set forth in Patent Number 1,004,879, granted to me on October 3rd, 1911, for heel fasteners.

Among the advantages attained by my invention over prior constructions are the improved manner in which the resilient detachable heel is mounted upon the fastener and the heel secured to the shoe and the particular means provided for assisting in positioning the resilient detachable heel and its fastener upon the shoe.

Further advantages attained by my invention will be pointed out in the following description.

In the accompanying drawing forming part of this specification, Figure 1 is a plan looking down upon my improved resilient heel with my improved fastener in place therein; Fig. 2 is a section taken upon the line A—A of Fig. 1; Fig. 3 is a perspective of my improved heel with the fastener removed; Fig. 4 is a section taken upon the line B—B Fig. 1; Fig. 5 is a detail of a shoe partly in section showing my improved heel and fastener mounted thereon, said heel and fastener being illustrated in section upon the line C—C, Fig. 1; Fig. 6 is a longitudinal central section of an alternative construction of my invention and Fig. 7 is a perspective of the heel illustrated in Fig. 6 with the fastener removed.

In the drawing is illustrated a portion of a shoe D having a counter 2, sole 3 and a heel base 4, which may be of any desired thickness or may be omitted entirely. A heel E formed of rubber or other suitable resilient material is adapted to be attached to

the shoe by a fastener F for which the heel E is suitably recessed at G. The fastener F is in the form of a plate 5 punched from a flat piece of sheet metal having forwardly and rearwardly rim portions 6 and 7 which are adapted to be bent upwardly at right angles to the plane of the plate. At the corners of the upturned portions are acute marking points 8 which extend upward in the completed form of the device as shown in Fig. 2, and having one face 9 oblique and one face 10 normal to the surface of the heel base. From the lateral sides of the plate 5 extend rim portions 11 and 12. These side rim portions are at right angles to the plane of the surface of the plate and are formed with spaces or openings 13 and 14 between them through the body of the plate which in turn produce a bridge 15 connecting the forward and rearward ends of the plate for reinforcing purposes. Holes 16 are punched in the plate 5 through which nails 17, screws or other suitable means of attachment for the shoe may be passed. The rim portions 6, 7, 11 and 12 are of substantially the same height above the plate and form a rim which is adapted to rest against the lower surface of the heel base 4 of the shoe on its middle line with the bridge 15 downward.

From the lateral sides of the plate 5 project flanges 18 and 19 extending from the forward to the rear ends of the sides. These flanges are formed with rounded sides and lie adjacent to each other with a V shaped opening 20 in each flange between its ends. In this position the nails 17 are driven upward through the holes 16 and heel base and attach the fastener firmly to the shoe. The points 8 are adapted to be fixed in the leather of the heel base 4 and assist in serving to take the lateral strain from the nails 17. The nails 17 together with the points 8 are strong enough to resist all of the usual stresses of a rubber heel attached to the fastener F when in service.

The heel E has the usual outer design which together with the heel base 4 make up a heel of the proper height for a shoe. In the top of the heel is the cavity G fitted to the exterior of the rim formed by the rim portions 6, 7, 11 and 12 and fitting snugly over them when the heel E is in its proper position on the shoe. Below the top of the heel the cavity G is recessed laterally to receive the flanges 18 and 19, the resilient material being left in the form of a web 21 to

fill the V shaped space between the flanges on each side of the fastener. The flanges 18 and 19 being of the same form on the two sides of the fastener, the recesses in the 5 silent heel E are of the same form on the two sides of the heel, and the heel may be put on from either side equally well, which prevents the delay and possible injury to the heel from putting a heel on wrong on 10 to an unsymmetrical fastener, and also permitting heels on a pair of shoes being interchanged to produce even wear and longer life. The bottom of the cavity G in the rubber heel is formed with protuberances 22 15 and 23 equalizing in height the thickness of the plate 5. These protuberances are similar in shape to the spaces or openings 13 and 14 in the plate and serve to strengthen the engagement between the resilient heel and the 20 fastener and prevent all longitudinal and lateral movement between said parts. Thus the heel on its mounting is strengthened materially over a construction wherein protuberances of the character set forth are not 25 provided between said parts.

The upper surface 24 of the heel is concave, its marginal edge 25 around the entire heel lying in a single plane. This concavity causes the marginal edge to lie in the same 30 plane with the extremities of the points 8 thus enabling the heel E to be placed upon the portion 4 to mark the position of the fastener which is inserted in place. When so positioned a sharp impact against the 35 lower surface of the detachable heel causes the points 8 to indent the lower surface of the heel base 4. After marking the position of the fastener on the heel base, the fastener is removed from the detachable heel and secured in position according to said indentations 40 on the heel base by the nails 17 and the detachable heel is then sprung into position on the fastener. The detachable heel is thus adapted to be secured in place under 45 tension or compression causing a firmer hold by suction upon the heel base and forming a tighter joint between it and the base. This is obviously an advantage because the mounting is stronger and the joint neater in 50 appearance, not allowing any moisture or foreign matter to creep into the cavity G.

In the alternative construction the fastener 26 is of substantially the same design as the preferred, excepting that it is made 55 out of cast material instead of being stamped from a plate. The protuberances instead of being formed in the detachable heel are of single form produced on the lower surface of

the fastener 26 and the heel formed with a space or depression 27, the margin of which 60 fits snugly over the margin of the protuberance 28 on the fastener.

In accordance with the patent statutes I have described the principles of operation of my invention together with the apparatus 65 which I now consider to represent the best embodiment thereof but I desire to have it understood that the construction shown is only illustrative and that the invention can be carried out by other means and applied 70 to uses other than those above set forth within the scope of the following claims.

Having described my invention, what I claim as new and desire to protect by Letters Patent is:—

1. A fastener for a resilient shoe heel comprising a body having a rim portion to space it from the heel of the shoe and a flange projecting laterally from said body, in combination with a recessed resilient heel arranged 80 to be sprung over said body and flange to engage with the same, one of said parts having a protuberance and the other an opening in which said protuberance is arranged to engage to assist in preventing lateral displacement of said heel from said body. 85

2. In combination, a fastener arranged to be permanently attached to a shoe and having means for separately engaging a resilient shoe heel and integral marking points to 90 position said fastener on the shoe, a resilient heel in which said fastener is engaged having a concave face lying adjacent the shoe, the rim of which being arranged as regards the extremities of said points to prevent said 95 points normally engaging the surface of the shoe when the heel with the fastener therein is positioned on the shoe previous to marking, leaving said points free to engage the material of the shoe by the compression 100 of said heel against the shoe and means for permanently attaching said fastener with the material of the shoe impinged upon said points, the margin of said heel being arranged to press under stress against the surface of the shoe to hermetically seal the joint between the heel and shoe when said heel is detachably secured over said permanently attached fastener on said shoe. 105

In testimony whereof, I have signed my 110 name to this specification in the presence of two subscribing witnesses.

FRANCIS A. NOLAN.
